INKING MECHANISM FOR PRINTING MACHINES

William F. Huck, Richmond Hill, N. Y., assignor to R. Hoe & Co., Inc., New York, N. Y., a corporation of New York

Application October 5, 1942, Serial No. 460,871

15 Claims. (Cl. 101—350)

This invention relates to printing machines, and more particularly to improved ink distributing mechanisms for rotary printing units in which ink is fed under pressure from ink rails to ink receiving cylinders which form components of rotary ink distributing mechanisms which are constructed and arranged to work the supplied ink into a uniform film and deposit it on rotary printing forms.

In existing inking mechanisms of this type, the ink distributing cylinders and rollers usually rotate in one direction, and the ink is supplied to a selected ink cylinder of each ink distributing mechanism from an ink rail which has an arcuate face that is held adjacent the ink cylinder at one side thereof, so that the ink is deposited on the peripheral surface of the cylinder.

A commercial demand now exists for printing units in which the printing cylinders and the components of the ink distributing mechanisms rotate in both forward and reverse directions to permit the webs to be run in both directions through the units.

It is an object of this invention to provide an improved inking mechanism for rotary printing units in which ink is supplied under pressure from an ink rail to an ink receiving cylinder in such manner that the cylinder may be rotated in forward and reverse directions.

Another object of this invention is to provide an improved inking mechanism for rotary printing units in which ink is supplied under pressure from an ink rail to an ink receiving cylinder in such manner that the cylinder may be rotated in forward and reverse directions, the ink rail being adjustable for movement to and from the cylinder and which is yieldingly supported in any selected adjusted position.

A further object of this invention is to provide an improved inking mechanism for rotary printing units in which ink is supplied under pressure from an ink rail to an ink receiving cylinder in such manner that the cylinder may be rotated in forward and reverse directions, the ink rail being adjustably movable by power driven means and securable in predetermined positional relation to the periphery of the ink receiving cylinder and yieldingly supported in this position.

An additional object of this invention is to provide an improved inking mechanism for rotary printing units in which ink is supplied under pressure from an ink rail having an arcuate face to an ink receiving cylinder in such manner that the cylinder may be rotated in forward and reverse directions, the ink rail being adjustable to dis-

pose its arcuate face in eccentric relation to the peripheral surface of the ink receiving cylinder.

A specific object of this invention is to provide an improved inking mechanism for rotary printing units in which ink is supplied under pressure from an ink rail having an arcuate face to an ink receiving cylinder in such manner that the cylinder may be rotated in forward and reverse directions, the ink rail being adjustable for movement radially to and from the cylinder and yieldingly supported in any selected adjusted position, the ink rail also being laterally adjustable to dispose its arcuate face in eccentric relation to the peripheral surface of the cylinder so that the space defined between the peripheral surface of the cylinder and the arcuate face of the rail is narrower at the ink discharge side of the rail than at its opposite side.

It is also an object of this invention to provide an improved inking mechanism for rotary printing units whereby the improved mechanism will be simple, durable, and inexpensive in construction, as well as convenient, practical, serviceable, and efficient in its use.

With the foregoing and other objects in view, which will appear as the description proceeds, the invention resides in the combination and arrangement of parts and in the details of construction hereinafter described and claimed, it being understood that various changes in form, proportion and minor details of construction may be made within the scope of the claims without departing from the spirit or sacrificing any advantages of the invention.

For a complete disclosure of the invention, a detailed description thereof will now be given in connection with the accompanying drawings forming a part of the specification wherein:

Figure 1 is an end elevation of a rotary printing unit having the device forming the subject matter of this invention applied thereto;

Figure 2 is a side elevation of the printing unit depicted in Figure 1, and showing the invention applied thereto;

Figure 3 is an enlarged fragmental side elevation, seen in the same direction as Figure 2, parts being shown in section;

Figure 4 is a vertical sectional view taken on the line 4—4 of Figure 3, remote parts being omitted;

Figure 5 is a fragmental view similar to Figure 4, but showing the improved ink rail in a different cooperable position with relation to the ink receiving and distributing cylinder; and

Figure 6 is a horizontal sectional view taken on the line 6—6 of Figure 5.

Referring to the drawings, in which similar reference characters designate corresponding parts, there is depicted a modern rotary printing unit 10 to which the invention is applied and which is best seen in Figures 1 and 2. This is a newspaper printing unit, although it is to be understood, of course, that the improved ink rail construction and arrangement may be readily applied to other types of rotary printing machines. The unit includes a frame having side members 11 which rotatably support two printing couples, and each printing couple includes an impression cylinder 12 and a plate or form cylinder 13, which cylinders are rotatably mounted in suitable bearings 15 carried by the frame side members 11.

Each plate or form cylinder 13 has ink supplied thereto through an ink distributing mechanism, and each ink distributing mechanism including an upper ink distributing cylinder 16 and a lower ink receiving and distributing cylinder 17 operably supported by the machine frame in conventional manner. The ink distributing cylinders 16 and 17 are operably engaged by conventional ink distributing and transfer rollers 18, and the plate cylinders 13 are operably engaged by conventional form rollers 20 which also engage the upper ink distributing cylinder 16.

This arrangement permits convenient application of the invention thereto, although it is to be understood, of course, that the invention may be applied to other forms of printing units and ink distributing mechanisms thereof.

Ink is supplied to each ink receiving and distributing cylinder 17 from an improved ink rail 22 which extends across the printing unit in parallel relation to the ink receiving cylinder 17, and it is adjustably supported at its opposed terminals, as disclosed hereinafter. The ink rail 22 supports a conventional ink pump 23 at one terminal thereof, and ink is forced from this pump through separate conduits 25 that are housed or nested in a longitudinally extending recess 26 formed in the ink rail 22, and each conduit communicates with an ink discharge throat or orifice 27 (Figures 3, 4, 5) formed in the upper portion of the ink rail. The ink rail may be formed of a single piece of material, but a preferred arrangement is one in which its upper terminal is formed by providing rail sections 22a and 22b (Figures 4 and 5) which are secured to a projection 24 formed at the upper terminal of the rail body by screws 28 (Figure 5), or other suitable securing devices. Each ink rail is preferably rectangular in cross section, and has an arcuate or cylindrical face 29, the axis of which is located in a vertical plane that passes through the central portion of the rectangular ink rail, and the radius of the cylindrical face 29 is substantially the same as the radius of the periphery of the ink receiving cylinder 17. Slide blocks or brackets 30 (Figures 4, 5, 6) are rigidly secured in opposition to the lateral face of the ink rail 22 adjacent its terminals by screws 33 (Figure 4), or other suitable securing devices. Each block 30 is bifurcated at its upper and lower terminals to provide recesses which receive rollers 31, and each roller 31 is rotatably supported on a pin or shaft 32 carried by a bifurcated terminal of the bracket 30.

The peripheral faces of the rollers 31 engage adjusting bars or gibs 35 which are loosely received in gib-ways or recesses 36 formed in vertically-disposed gib supports or members 37 located in opposition at the sides of the ink rail 22 adjacent

each terminal thereof. Each gib 35 is supported for lateral or transverse movement in its gib-way 36 by pins 38, which are carried by the gib and loosely received for axial movement in cylindrical recesses 40 formed in each gib support 37. Each gib support has threaded apertures 41 or 41a extending laterally therethrough adjacent its upper and lower terminals for the reception of screws 42 of determined length, and these screws have enlarged heads 43 provided with radial apertures for the reception of a conventional pin wrench, not shown. When the screws 42 are threadedly received in the apertures 41 (Figure 4) with their heads in engagement with the outer surfaces of the gib supports 37, the opposed terminals of the screws engage a gib and force the gib inwardly, so that the inner longitudinal face of the gib is spaced a short distance from and in parallel relation with the vertical back wall of the gib-way 36, for a reason to be hereinafter explained.

A guide plate 45 is secured to the outer face of each gib support 37 by screws 46 which extend through cylindrical apertures formed in the guide plate 45 and gib support 37 and are threaded into a side member 11 of the machine frame to thereby rigidly secure each guide plate 45 to its gib support 37, and each gib support to the side member 11 of the machine frame. The inner longitudinal portion of each plate 45 overhangs the inner portion of each gib support 37 to define a guideway 47 between the outer face of the supporting side member 11 and the inner face of the guide plate 45 to slidably receive a bracket or slide block 30. By this arrangement, the ink rail 22 is guided for vertical adjustment relative to the ink receiving cylinder 17 by the sliding movement of each block 30 in its guideway 47, and the rolling engagement of the rollers 31 with the gibs 35.

Cylindrical elevating members or screws 50 and 50a (Figure 2) are rotatably received in cylindrical apertures 51 formed in the ink rail body adjacent its longitudinal terminals, and each screw is held against axial movement in its aperture 51 by a screw 52 that has a cylindrical inner terminal which is received in an annular groove 53 formed in the shank of each screw. A sprocket 54 is secured to the shank of each screw below the ink rail 22, and a bearing ring or washer 55 surrounds the shank of the screw and is interposed between the sprocket 54 and the lower surface of the ink rail. A chain 56 is trained around the sprocket 54 so that the screws 50 and 50a rotate in unison. The screw 50 has a gear 57 secured to its shank by a set screw 58 which extends through the hub of the gear and engages the shank of the screw, and this gear meshes with a pinion 60 carried by a shaft 61 which is driven from an electric motor 62 through a conventional speed reducing mechanism indicated at 63. The screw 50 has a larger diameter portion 64 preferably formed integral therewith that abuts the lower terminal of the hub of the gear 57 to maintain it in position when the set screw 58 is loosened, and also to support the ink rail 22. The lower portion of each screw 50 or 50a is threaded, as indicated at 65, to threadedly engage similar threads formed in the inner portion of a bushing 66 (Figure 4) which has an enlarged head or flange 67 formed at its lower terminal. Each bushing 66 is slidably received in a cylindrical aperture formed in the lower portion of a bracket 69 which is provided with a supporting flange 70 that is secured to a side member 11 of the machine frame, and each bushing is held against rotatable movement relative to the bracket 69.

by pins 71 which are carried by the bushing and are received for axial sliding movement in recesses 72 formed in the lower portion of the bracket 69. Each bracket 69 has a cylindrical recess 73 formed therein for the reception of helical compression springs 75, which springs engage the end wall of the cylindrical recess 73 at their lower terminals, and the upper terminals of these springs engage an adjusting collar 76 which is threadedly secured to the outer threaded portion 77 of the bushing 66. Radially extending apertures 78 are formed in the collar 76 for the reception of a pin wrench, not shown, in order that the collar 76 may be rotated in relation to the bushing, for a reason to be hereinafter explained. A lock nut 79 threadedly engages the threaded portions 77 of each bushing 66 in order to lock the adjusting collar 76 in any selected position with relation to its bushing.

The motor and gear arrangement provides power means for rotating the screws 50 and 50a, as will be more fully explained hereinafter, and the screws 50 and 50a also have wrench engaging surfaces 80 formed at their upper terminals for the reception of a wrench or crank, not shown, so that the screws 50 may be manually rotated by loosening the set screw 58.

Each side member 11 of the machine frame is provided with an opening 82 (Figure 3) which receives the ink rail 22 and permits free vertical movement of the rail therein. A stop or limit screw 83 is threadedly secured to the upper portion of the ink rail adjacent each terminal and is located to abut the upper wall 85 of the opening 82 to limit the upward movement of the ink rail, for a purpose to be hereinafter explained. Each screw 83 is provided with a wrench engaging portion, to permit the screw to be rotated so that its upper terminal is positioned a predetermined distance above the upper portion of the ink rail.

A conventional limit switch 86 is supported below the screw 50 in alignment therewith, in order to actuate the switch when the screw has been moved to its lowermost position. A similar limit switch 87 is supported immediately below and in alignment with a lug or projection 88 carried by the head 67 of the bushing, so that downward movement of the bushing will actuate this limit switch. The limit switches 86 and 87 are of conventional construction and are located in a conventional motor control electric circuit and operate to stop the motors at the upper and lower limits of travel of the ink rail, as will be more fully explained hereinafter. The motors are controlled by the usual push button in the electric circuit, and these buttons may be located at any convenient place to control the operation of the motor. Inasmuch as the electric motor control circuit is well known by those skilled in the art, the circuit has not been illustrated in this application.

When the motor 62 is employed to raise and lower the ink rail 22 for cooperable relation with the periphery of the ink cylinder 17, the electric circuit is established to rotate the motor, which, in turn, rotates the screws 50 and 50a through the drive pinions 60, gear 51, sprockets 54 and chains 56.

In operation, when the web W of the printing unit 10 is being run through the unit in such direction as to cause the ink cylinder 17 to rotate in clockwise direction (Figure 4), the ink rail 22 is adjusted for such operation by manipulating the screws 42 to locate the arcuate face 29 of the ink rail 22 in desired positional relation to the

peripheral surface of the ink cylinder 17. This adjustment is made by simply inserting the screws 42 in the threaded apertures 41 in the left hand gib support 37. When these screws are screwed "home" by a pin wrench or other suitable tool, not shown, which is received in the apertures formed in the large head 43 of each screw, the inner terminals of the screws 42 engage the left gib 35, as viewed in Figure 4, and forces this gib a slight distance outwardly, but maintains it in parallel relation to its gib-way 36. This gib, in turn, engages the rollers 31 located at the left side of the ink rail and forces the ink rail to the right. This lateral movement of the ink rail also moves the gib at the opposed side of the machine to its inner lateral limit within its gib-way. In this relationship, when the ink rail 22 has been adjusted by rotating the screws 50 and 50a, either by power or manually, so that the left terminal of its 20 arcuate face 29 contacts or is positioned immediately adjacent the peripheral surface of the cylinder 17, an arcuate gap or space is formed between the peripheral surface of the ink cylinder 17 and the arcuate face 29 of the rail, the gap progressively widening as the opposite side of the rail is approached, thus establishing an eccentric relationship between the arcuate face 29 of the ink rail and the peripheral surface of the ink cylinder 17. The upward movement of the ink rail 22 is 25 limited by the contact of its arcuate face 29 with the peripheral surface of the ink cylinder, or, if preferred, the contact of the stop screws 83 with the stop surfaces 85 (Figure 3) formed in the side member 11 of the machine frame. The yieldable support of the ink rail and the eccentric relationship between the arcuate face 29 of the ink rail and the peripheral surface of the ink cylinder 17 permits the ink rail to be so adjusted with relation to the ink cylinder as to substantially close 30 the space between the ink rail and the cylinder at the ink discharge side of the rail. Although the discharge side of the rail substantially engages the surface of the ink cylinder 17, a gradually widened space is provided as the opposite side is approached, thus allowing ample space between the rail and cylinder to receive the supplied ink from the rail outlet orifices 27.

In this arrangement, the rail 22 may be adjusted much closer to the ink cylinder 17 than is possible with the conventional ink rail where the rail is rigidly secured to the frame of the machine, in which case the setting must be such that there is ample space between the ink rail and cylinder to allow the passage of the maximum amount of ink required in a printing operation. In this improved arrangement, if the ink requirement for the printing operation is greater than the amount of ink that could be supplied from the discharge side of the ink rail, then the rail will be crowded downwardly away from the cylinder by the supplied ink, so that the requisite quantity is fed from the rail to the cylinder in a uniform film.

If the direction of operation of the printing unit is to be reversed, then the screws 42 are removed from the apertures 41 in the left gib support, as viewed in Figure 4, and positioned in the apertures 41a in the right support 37, as shown in Figures 5 and 6. In this location, the right hand gib is forced towards the ink rail thereby moving an ink rail to such positional relationship to the ink distributing cylinder 17 that the arcuate gap defined between the periphery of the ink distributing cylinder 17 and the arcuate face 29 of the ink rail is progressively widened as the left

hand side of the rail is approached. In this relationship, the ink cylinder 17 is operated in a counter-clockwise direction, as indicated by the arrow in Figure 5, but the ink feeding operation is similar to that hereinbefore described.

When the ink rail 22 is to be moved away from the ink distributing cylinder 17, the motors 62 are operated in reverse direction, thus causing the hereinbefore disclosed drive mechanism to move the supporting screws 50 and 50a and ink rail downwardly. If the supporting screw 50 reaches its lower limit of movement it engages the limit switch 86 and opens the electric circuit to the motor, thereby discontinuing its operation. In adjustably moving each ink rail 22 towards the ink distributing cylinder 17, the upward movement of the rail is limited, as stated, by the engagement of the arcuate surface 29 of the rail with the peripheral surface of the ink distributing cylinder 17, or by the engagement of the stop screws 83 with the stop surfaces 85. After the upward movement of a rail is arrested, continued rotation of its supporting screws will cause the bushings 66 to move downwardly against the tension of the springs 75 until the projection 88, carried by the head 61 of the bushing, engages the limit switch 87 to open the circuit to the motor.

In black printing, or in printing of a character that does not require frequent cleaning of the components of the printing unit, the motors 62 may be omitted, and the adjustment may then be manually made by simply applying a wrench or crank, not shown, to the rectangular heads 80 of the screws 50, thereby rotating these screws to adjustably move the ink rail.

In color printing, or other printing of the character where frequent cleaning of the unit components is necessary, motor operation is preferable and hand operation is resorted to only in case of motor failure.

With the construction and arrangement disclosed in this application, a uniform film of ink is supplied to each ink receiving cylinder 17, and the ink cylinders may operate in either forward or reverse direction.

In the commercial use of this device the ink rail, in most instances, is located below the axis of an ink cylinder, but in certain color combinations, units are provided in which the inking mechanism and printing cylinders are so arranged that the ink rail is located above the ink cylinder to which the ink is applied by the rail.

It will be understood that the invention may be embodied in other specific forms without departing from the spirit or essential attributes thereof, and it is therefore desired that the present embodiment be considered in all respects as illustrative and not restrictive.

What I claim is:

1. In a force feed inking mechanism for a printing machine having a rotatable ink cylinder, an ink rail having an arcuate face substantially conforming to the periphery of the ink cylinder and a plurality of ink outlets in the arcuate face arranged in parallel relation to the axis of the ink cylinder and from which ink is fed under pressure to the periphery of the cylinder, power operated means to move the rail vertically towards and away from the cylinder to locate it in feeding relation to the periphery of the cylinder with the midpoint of the arcuate face and ink outlets positioned below the cylinder and substantially in a vertical plane which passes through the cylinder axis.

2. In a force feed inking mechanism for a

printing machine having a rotatable ink cylinder, an ink rail having an arcuate face substantially conforming to the periphery of the ink cylinder and a plurality of aligned ink outlets located at the intermediate portion of the arcuate face from which outlets ink is fed under pressure to the periphery of the cylinder, the arcuate face of the ink rail being located below the cylinder in ink feeding relation thereto with its intermediate portion and ink outlets positioned vertically below the axis of the cylinder whereby ink may be fed to the cylinder periphery from the outlets and move upwardly with the cylinder from the ink rail at either side thereof, and power operated means to move the rail vertically towards and away from the cylinder.

3. In a force feed inking mechanism for a printing machine having a rotatable ink cylinder, an ink rail having an arcuate face substantially conforming to the periphery of the cylinder and a plurality of ink outlets from which ink is fed to the cylinder, and means to position the ink rail in ink feeding relation to the cylinder with its arcuate face slightly eccentric to the cylinder periphery whereby the space between the said arcuate face and the cylinder periphery may be greater at one side of the ink rail than at the other.

4. In a force feed inking mechanism for a printing machine having a rotatable ink cylinder, an ink rail having an arcuate face substantially conforming to the periphery of the cylinder and a plurality of ink outlets from which ink is fed to the cylinder, means to move the rail toward and away from the cylinder, and means to position the rail in ink feeding relation to the cylinder with its arcuate face slightly eccentric to the cylinder whereby the space between the said arcuate face and the cylinder periphery may be made greater at one side of the ink rail than at the other.

5. In a force feed inking mechanism for a printing machine having a rotatable ink cylinder, an ink rail having an arcuate face substantially conforming to the periphery of the ink cylinder and ink outlets located at the intermediate portion of the arcuate face from which outlets ink is fed under pressure to the periphery of the cylinder, the arcuate face of the ink rail being located below the cylinder in ink feeding relation thereto with its midpoint positioned substantially vertically below the axis of the cylinder whereby ink may be fed to the cylinder periphery from the outlets and move upwardly thereon from the ink rail at either side thereof, means to move the rail towards and away from the cylinder, and means to position the ink rail with its arcuate face slightly eccentric to the cylinder periphery whereby the space between the said arcuate face and the cylinder periphery may be greater at one side of the ink rail than at the other.

6. In a force feed inking mechanism for a printing machine having a rotating ink cylinder, an ink rail having an arcuate face substantially conforming to the periphery of the cylinder and a plurality of ink outlets in the arcuate face from which ink is fed to the cylinder periphery, means to yieldingly support the ink rail for radial movement away from the cylinder, and means to position the ink rail in ink feeding relation to the cylinder with its arcuate face disposed slightly eccentric to the cylinder whereby the space between the said arcuate face and the cylinder periphery is less at the ink discharge

side of the rail than at the other so that the pressure of the ink in the space between the arcuate face and the periphery of the rotating ink cylinder will force the yieldably supported ink rail away from the cylinder sufficiently to accommodate the required quantity of feeding ink.

7. In a force feed inking mechanism for a printing machine having a rotatable ink cylinder, an ink rail having an arcuate face substantially conforming to the periphery of the ink cylinder and ink outlets from which the ink is fed under pressure to the cylinder periphery, means to move the entire rail radially towards and away from the cylinder and yieldingly support the rail in any selected position, and means to move the rail tangentially with respect to the ink cylinder to position the ink rail so that its arcuate face is disposed in eccentric relation to the cylinder periphery whereby the space between the said arcuate face and the cylinder periphery may be greater at one side of the rail than at the other.

8. In a force feed inking mechanism for a printing machine having a rotatable ink cylinder, an ink rail having an arcuate face substantially conforming to the periphery of the ink cylinder and ink outlets from which the ink is fed under pressure to the cylinder periphery, power driven means to move the entire rail radially towards and away from the cylinder and yieldingly support the rail in any selected position, and means for automatically discontinuing the operation of the power driven means when the ink rail has reached the limits of its intended movement towards and away from the ink cylinder.

9. In a force feed inking mechanism for a printing machine having a rotatable ink cylinder, an ink rail having an arcuate face substantially conforming to the periphery of the ink cylinder and ink outlets from which the ink is fed under pressure to the cylinder periphery, guide members to support the ink rail for radial movement towards and away from the ink cylinder, means for moving the entire rail along the guide members towards and away from the cylinder, and means for moving the guide members perpendicular to the direction of radial movement of the ink rail to thereby position the ink rail with its arcuate face slightly eccentric to the cylinder periphery whereby the space between the said arcuate face and the cylinder periphery is greater at one side of the rail than at the other.

10. In a force feed inking mechanism for a printing machine having a rotatable ink cylinder, an ink rail mounted for movement radially to and from the ink cylinder, the ink rail having apertures therein radially-disposed relative to the ink cylinder and having an arcuate face substantially conforming to the periphery of the ink cylinder and ink outlets in the face from which the ink is fed under pressure to the cylinder periphery, screws received in the apertures and rotatable relative to the ink rail and operable to move the entire ink rail radially towards and away from the cylinder, means to simultaneously rotate the screws, and means to position the arcuate face of the ink rail eccentrically to the cylinder, whereby the space between the said

arcuate face and the cylinder periphery is less at the ink discharge side of the rail than at the other side thereof.

11. In a force feed inking mechanism for a printing machine having a rotatable ink cylinder, an ink rail having an arcuate face substantially conforming to the periphery of the ink cylinder and ink outlets from which the ink is fed under pressure to the cylinder periphery, a screw rotatably secured to the ink rail and operable to move the entire ink rail radially towards and away from the cylinder, means to rotate the screw, and means to yieldingly support the screw to thereby yieldingly support the rail in any selected position relative to the ink cylinder.

12. In a force feed inking mechanism for a printing machine having a rotatable ink cylinder, an ink rail having apertures therein radially-disposed relative to the ink cylinder and an arcuate face substantially conforming to the periphery of the ink cylinder and ink outlets in the face from which the ink is fed under pressure to the cylinder periphery, a guide to support the ink rail for radial movement towards and away from the ink cylinder, screws received in the aperture and rotatably secured to the ink rail and operable to move the entire ink rail radially along the guide towards and away from the ink cylinder, means to simultaneously rotate the screws, and means to yieldingly support the rail in any selected position relative to the ink cylinder.

13. In a force feed inking mechanism for a printing machine having a rotatable ink cylinder, an ink rail having an arcuate face substantially conforming to the periphery of the ink cylinder and ink outlets from which the ink is fed under pressure to the cylinder periphery, guide members to support the ink rail for radial movement towards and away from the ink cylinder, a screw rotatably secured to the ink rail and operable to move the entire ink rail radially along the guide members towards and away from the ink cylinder, means to rotate the screw, and means to yieldingly support the rail in any selected position relative to the ink cylinder.

14. In a force feed inking mechanism for a printing machine having a rotatable ink cylinder, an ink rail having an arcuate face substantially conforming to the periphery of the ink cylinder and a plurality of aligned ink outlets in vertical alignment with the axis of the ink cylinder from which outlets ink is fed under pressure to the cylinder periphery, means to move the entire rail vertically toward and away from the cylinder, and means to yieldingly support the rail in any selected position.

15. In an inking mechanism for a printing machine, a rotatable ink cylinder, an ink rail disposed in substantially parallel relationship to the ink cylinder, an arcuate face for the ink rail the radius of which is substantially equal to the radius of the ink cylinder, and means to position the ink rail in ink feeding relation to the cylinder with its arcuate face disposed eccentrically to the cylinder, whereby the space between the said arcuate face of the cylinder periphery is less at the ink discharge side of the rail than at the other side.
